UNITED STATES PATENT OFFICE.

EDGAR HOWARD REED, OF WORCESTER, MASSACHUSETTS.

METHOD OF MAKING WINGED NUTS AND THE LIKE.

1,399,793.

Specification of Letters Patent.

Patented Dec. 13, 1921.

Application filed March 13, 1920. Serial No. 365,592.

To all whom it may concern:

Be it known that I, EDGAR HOWARD REED, a citizen of the United States, residing at Worcester, in the county of Worcester and State of Massachusetts, have invented a new and useful Method of Making Winged Nuts and the like, of which the following is a specification.

The principal objects of this invention are to provide for shaping wing or thumb nuts and articles of similar shape from wire or cylindrical blanks in a way that will necessitate fewer operations in shaping the nut than has been the case with the methods heretofore employed for making them of wire, and thus produce less distortion of the metal and produce a nut more nearly of the shape made by drop forge process.

I accomplish these results, generally speaking, by forming the articles from a blank consisting of a piece of wire originally of the diameter of the nut proper so that that part of the nut does not have to be formed or its shape changed, and a characteristic feature of the process consists in the fact that the entire blank is confined in the dies and the pressure on the blank is exerted in the direction of the axis thereof, instead of in a transverse direction as has been the case heretofore. Further objects and advantages of the invention will appear herein.

Reference is to be had to the accompanying drawings, in which—

Figure 1 is a perspective view of a piece of metal rod or wire which constitutes the original blank from which the article is to be made;

Fig. 2 is a similar view showing the blank at an intermediate stage of its manufacture; Fig. 3 is a similar view of the completed article;

Fig. 4 is an elevation partly in section of the first set of dies;

Fig. 5 is a plan of the lower die, and

Fig. 6 is a side view of one of the half dies used in the finishing operation.

In accordance with this invention, a blank A is formed from a piece of wire or cylindrical rod of the desired metal, cut off square at each end, the length, of course, being determined by the amount of metal required to form the article.

If the article to be produced is a wing nut as C, the blank A is first put through an upsetting operation in dies to produce an intermediate result shown at B. It is to be

understood that this invention is not limited to the making of wing nuts, as it can be used for the manufacture of other articles of a similar nature in which there is a central body as c, shown as cylindrical in this case, and arms or wings as c² projecting therefrom. It is to be noted that in the intermediate stage there is a central body b of cylindrical shape and of the same diameter as the blank A, which is a part of that blank unmodified in shape but of less length. This intermediate body also has arms b' which in this instance extend from it in opposite directions and are formed by upsetting the metal of the blank A. These arms are eventually shaped to form wings c².

For the purpose of forming the intermediate blank B from the original blank A, a pair of dies are employed. A female die 10 has a central passage in which is a cylindrical plunger 11, which furnishes the bottom of the die and constitutes an ejector for ejecting the article from it. This plunger is of the same diameter as the blank A. The passage which receives the plunger 11 continues clear up through to the top of the die to form a cylindrical cavity 12 high enough to receive the original blank A resting on the top of the plunger 11 when that is in the position shown in Fig. 4. This cavity 12 constitutes an important feature of the die which is also provided with two recesses 13 in the present instance on opposite sides of the cavity 12 and communicating therewith. These recesses are inclined at their lower surfaces in the form shown.

The male part of the die consists of a support 15 having a plunger below it provided with a cylindrical central portion 16 and two opposite projections 17 having inclined lower surfaces 18 and rounded ends.

The operation consists in placing the blank A in the die 10 on top of the plunger and then, while keeping that plunger in stationary position and the blank confined between the dies throughout its length, forcing the plunger 15 down until the bottom surface of the projecting part comes to within the required distance of the bottom surface of the cavity in the die 10 and the upper surface of the plunger 11. This results in upsetting the metal throughout the length of the blank A into the cavities 13 under the projections 17 so as to form the projections b' on the blank which in this stage I have designated B, and that blank is the result of this

process. The plunger 15 is then withdrawn as indicated by the arrow and the plunger 11 forced up to eject this blank. It will be understood that the relative motion of the 5 parts to secure these results can be obtained by moving the die 10 instead of the plunger 15 if desired.

After the blank B is formed, it is placed between two dies 20, each one having a semi- 10 cylindrical cavity 21 and two recesses 22 communicating therewith and of such shape as to form the desired wings. This cavity 21 is of the same diameter as the blank A and the hub b, so that no work is done really 15 on this part of the blank, but the finishing dies come together on the blank B and give it its finished shape as shown at C in a way that will be readily understood.

The only thing necessary in order to complete 20 the wing nut C after it is operated upon in the dies 20, is to bore or pierce the central passage c³ and thread it, because the central nut portion and wings are entirely finished on their exterior surfaces by 25 the dies 20.

In this way, it will be seen that there is a material part of the article, namely the central hub or nut portion C, on which practically no work is required, thus eliminating 30 the necessity of working practically half of the metal in the article. Furthermore, only two operations are required in manufacture, a rough upsetting operation, and a finishing pressing operation, thus reducing the 35 number of steps ordinarily employed for making wing nuts out of wire. It will be understood of course, that when the invention is used for making other articles which come within its terms, the dies will be modified accordingly.

Although I have illustrated and described only a single series of steps and a single set of dies and have shown the invention as applied to the manufacture of one particular 45 article only, I am aware of the fact that the invention can be employed for the production of other articles of a similar nature and with modifications in the shape of the intermediate blank and both sets of dies 50 without departing from the scope of the in-

vention as expressed in the claims. Therefore I do not wish to be limited in these respects, but what I do claim is:

1. The method of making articles having a central main portion with projections 51 therefrom, which consists in upsetting a cylindrical wire blank in an axial direction without changing the shape of a portion of said original blank, and forming the projections from the metal originally in the body 61 of said blank and thereafter compressing the said projections laterally to finish them.

2. The method of making wing nuts and the like which consists in upsetting a cylindrical wire blank in an axial direction to 61 form wings thereon and maintaining a part of the blank substantially in its original shape and size to constitute the body of the nut, and thereafter finishing said wings by lateral compression without materially altering said body.

3. In a set of dies, the combination of a female die having a central longitudinal passage therein and recesses extending from 71 said passage sidewise, and a plunger having a central longitudinal portion and projections extending therefrom for entering said die and upsetting a blank standing therein to fill the said recesses with metal therefrom to provide projections on the central portion of 81 the blank.

4. In a set of dies, the combination of a female die having a central longitudinal passage all the way through it, an ejecting plunger in the bottom of said passage, and recesses extending from said passage sidewise immediately above the top of said plunger when in normal position, and an upsetting plunger having a central longitudinal portion and projections extending therefrom 91 with slanting lower surfaces for entering said die and upsetting a cylindrical blank resting on the first named plunger to fill the said recesses with metal therefrom to provide projections on the central portion of the 91 blank.

In testimony whereof I have hereunto affixed my signature.

EDGAR HOWARD REED.
